UNITED STATES PATENT OFFICE

RUDOLF MEINGAST AND MARTIN MUGDAN, OF MUNICH, GERMANY, ASSIGNORS TO
CONSORTIUM FUER ELEKTROCHEMISCHE INDUSTRIE, OF MUNICH, GERMANY

PROCESS OF MANUFACTURING ACETIC ANHYDRIDE

No Drawing. Application filed June 2, 1927, Serial No. 196,136, and in Germany June 16, 1926.

In carrying out the process of manufacturing acetic anhydride by heating acetic acid vapor to high temperatures, described for example in U. S. Patent No. 1,570,514 it is important for the heat transmitting surfaces of the heating chamber to be constructed of such material which has not only no undesired decomposing effect on the vapor of acetic acid, but has also a high thermal conductivity. As is known, the ordinary base metals decompose acetic acid vapor at temperatures of between 240 and 410° C., inclining especially to the formation of methane and carbon dioxide (Sabatier "La Catalyse" 2nd edition 1920, p. 328; Gmelin-Kraut, Handbuch der organ. Chemie, IV, Auflage, Bd. X. S. 624). For this reason the U. S. Patent No. 1,570,514 for carrying out the process as far as it is performed without the use of catalysts prescribes the absence of base metals.

The present invention relates to the application of our discovery, that a number of base metals which, according to the statements in the literature cited above are said to have a strongly decomposing action on acetic acid vapor, are applicable as materials for the heating apparatus in the process in question. This is the case particularly with the acid resisting chromium-iron alloys such as "duraloy" of the Duraloy Co., Pittsburgh, containing about 30% chromium, trace of silicon and carbon, and iron by difference, and the alloys "V2A", containing 20% chromium, 7% nickel, .25% carbon, iron by difference, "VM" and "nichrotherm", similar steel alloys having from 10-25% chromium and from 4-10% nickel, iron by difference, made by Friedrich Krupp in Essen, Germany.

Example I

150-1000 g. acetic acid vapor per hour are led thru a tube of 25 mm. diameter and 1 m. length made of the alloy V2A of Friedrich Krupp (containing besides iron 20% Cr, 7% Ni, 0.25% C) heated electrically to 400-800° C. preferably at 680° C. The product condensed at the exit of the reaction tube contains a considerable amount of acetic anhydride besides the equivalent quantity of water and the unchanged acetic acid. The

decomposition of the acetic acid in other directions is only very slight.

Example II

The procedure is the same as in Example I, but the V2A-tube is filled with the aluminum phosphate catalyst described in U. S. Patent No. 1,570,514, Example VI. In this case the condensed product contains 40-45 per cent acetic anhydride. The decomposition in by-products is again very unimportant.

Example III

The process is carried out in a tube of duraloy, containing the catalyst used in Example II. The result is the same as in Example II.

The heat conducting surfaces of the heating apparatus can be formed of electric heating resistances, by inserting the tubes themselves in the electric circuit or by arranging heating wires or bands etc. of the above metals or alloys within a container made of ceramic material, carbon, graphite or chromium alloys thru which acetic acid vapor is led.

What we claim is:

1. Process for preparation of acetic anhydride comprising heating acetic acid vapor to 400-800° C. on heat conducting surfaces composed of an alloy of chromium which does not decompose acetic acid at that temperature.

2. Process for preparation of acetic anhydride comprising heating acetic acid vapor in the presence of dehydrating catalysts to 400-800° C. on heat conducting surfaces composed of an alloy of chromium which does not decompose acetic acid at that temperature.

3. Process for the preparation of acetic anhydride comprising heating acetic acid vapor to 400-800° C. on heat conducting surfaces composed of an alloy of chromium and iron containing 10 to 30% chromium.

4. Process for the preparation of acetic anhydride comprising heating acetic acid vapor in the presence of dehydrating catalysts to 400-800° C. on heat conducting surfaces composed of an alloy of chromium and iron containing 10 to 30% chromium.

5. Process for the preparation of acetic anhydride comprising heating acetic acid vapor in the presence of a dehydrating catalyst to 400-800° C. on heat conducting surfaces composed of an alloy of chromium, iron and nickel, containing 10-25% chromium and 4-10% nickel.
